(57) **CLAIM**

The ornamental design for a sensor module, as shown and described.

DESCRIPTION

FIG. 1 is front view of a sensor module showing our new design in accordance with a first embodiment of the present invention;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is an upper front right perspective view thereof;

FIG. 8 is a reference perspective view thereof showing state in use;

FIG. 9 is a reference perspective view thereof showing state in use;

FIG. 10 is a front view of a second embodiment of a sensor module showing our new design;

FIG. 11 is a rear view thereof;

FIG. 12 is a left side view thereof;

FIG. 13 is a right side view thereof;

FIG. 14 is a top plan view thereof;

FIG. 15 is a bottom view thereof;

FIG. 16 is an upper front right perspective view thereof;

FIG. 17 is a reference perspective view thereof showing state in use; and,

FIG. 18 is a reference perspective view thereof showing state in use.

(Continued)

The broken line disclosure does not form part of the claimed design.

The dashed-dotted line showings of FIGS. 12-18 illustrate a boundary between the claimed design and environmental features and form no part of the claimed design.
